UNITED STATES PATENT OFFICE.

JACOB LIGHTER, OF MONTREAL, QUEBEC, CANADA.

DESIGN FOR A CATCH-HOOK.

49,930.

Specification for Design.

Patented Nov. 21, 1916.

Application filed February 7, 1916. Serial No. 76,871. Term of patent 7 years.

To all whom it may concern:

Be it known that I, JACOB LIGHTER, a subject of the King of Great Britain, residing at Montreal, Province of Quebec, Dominion of Canada, have invented a new, original, and ornamental Design for a Catch-Hook, of which the following is a specification, reference being had to the accompanying drawings, forming a part thereof.

Figure 1 is a perspective view of a catch

hook showing my new design; Fig. 2 a plan thereof; Fig. 3 a side elevation thereof; Fig. 4 an end elevation thereof.

I claim:

The ornamental design for a catch hook, as shown.

JACOB LIGHTER.
